UNITED STATES PATENT OFFICE.

JAMES F. McELROY, OF ALBANY, NEW YORK, SUSIE H. McELROY, EXECUTRIX OF SAID
JAMES F. McELROY, DECEASED, ASSIGNOR TO CONSOLIDATED CAR-HEATING COMPANY,
A CORPORATION OF WEST VIRGINIA.

ELECTRIC SWITCH.

1,191,326.

Specification of Letters Patent. Patented July 18, 1916.

Application filed February 27, 1912. Serial No. 680,230.

To all whom it may concern:

Be it known that I, JAMES F. McELROY, a citizen of the United States, residing at Albany, county of Albany, State of New York, have invented certain new and useful Improvements in Electric Switches, the following being a full, clear, and exact disclosure of the one form of my invention which I at present deem preferable.

For a detailed description of the present form of my invention, reference may be had to the following specification and to the accompanying drawings, which illustrate my invention.

Figure 1 is a vertical section of my device; Fig. 2 is a plan view thereof with the cover removed; Fig. 3 is a front view thereof with the casing in section.

My invention relates to a switch for an electric circuit and a fluid-pressure device for operating it.

Referring to the drawing, the main casing for the switch, shown at 410, is of somewhat cubical shape with an inwardly-extending guide-ring 411 for the piston rod. The cylinder 41 is outside of said casing and screwed into a boss thereon opposite the said guide-ring. At the outer end of cylinder 41 is a hollow casting 40 containing a chamber into which the compressed air enters. The piston 42 with its packing-ring 43 is pinned to the outer end of piston rod 44 which passes through and is guided by ring 411. On the inner end of rod 41 is mounted the carrier sleeve 45 detachably secured to the rod by a cotter-pin 48 and provided with a clamp 49 for the arched contact-bar of the switch and also with a radial rod 47 which loosely engages guide rod 46 to prevent axial rotation of the carrier, piston and piston rod. It will be observed that the pressure operating device thus described has a direct straight-line action on the switch, its stroke being equal to the range of throw of the switch itself.

The switch itself is shown at 5. The movable member is an arched contact-bar 50 which is coated with insulation except at its contact ends 50^a and 50^b and is held in the aforesaid clamp 49 on the carrier 45. The stationary contact terminals are two in number and each is in the form of two looped springs between which one end of contact-bar 50 is gripped. Thus one of the fixed

terminals comprises the looped springs 51^a and 51^b between which is gripped the contact end 50^a of the bar 50; the other comprises the looped springs 52^a and 52^b between which is gripped the contact end 50^b of the bar 50. Each fixed contact terminal is inclosed in a recess formed of insulating plates, one recess being formed by plates 53^a, 53^b and the other by plates 54^a, 54^b (see Figs. 2 and 3). Within these plates are embedded the pole-pieces of the blow-out magnets, which are not shown in detail since they form no part of my present invention. The circuit, entering by wire 70, goes to wire 71 and thence through one of the blow-out magnets to the terminal springs 51^a and 51^b. Thence, when the circuit is closed, it passes by bar 50 to the terminal springs 52^a and 52^b, and then, after passing through the other blow-out magnet, it goes by wire 72 to the outgoing wire 73.

By the arrangement above described the piston 42 has a straight-line stroke which drives the contact-bar 50 directly outward in a straight line to withdraw its ends 50^a and 50^b, directly outward away from the two fixed terminals to break the circuit. The circuit will remain closed so long as air pressure is maintained in cylinder 41. When that pressure is released a spring 60, interposed between the radial guide-arm 47 and the casting 40, comes into action and closes the circuit by driving the bar 50 into the grip of the fixed terminals. The radial rod 47 insures accurate entry of the bar into the terminals.

What I claim as new and desire to secure by Letters Patent is:

1. A switch of the character described comprising a casing, spaced apart insulating bars therein arranged in sets, the bars of each set being connected at one edge by an inner wall to form recesses, stationary contacts located within the recesses and extending parallel with said bars, a movable contact comprising an arched bar having end contacts extending approximately at right angles to said inner walls and movable parallel therewith, said end contacts overhanging said inner walls, and means for reciprocating said movable contact.

2. A switch of the character described comprising a casing provided with spaced apart elongated insulated recesses, station-

ary contacts parallel with the walls of said recesses, a movable contact comprising an arched bar having end contacts arranged at right angles to the stationary contacts and 5 movable parallel with the walls of said recess, and means for reciprocating said movable contact longitudinally of said recesses.

3. A switch of the character described comprising a casing provided with spaced 10 apart elongated insulating recesses, stationary contacts parallel with the walls of said recesses, a movable contact comprising an arched bar the ends of which extend into the

tops of said recesses at right angles to the bottom thereof and at right angles to said 15 stationary contacts and means for reciprocating said movable contact longitudinally of the recesses.

In witness whereof I have hereunto set my hand, before two subscribing witnesses, this 20 24th day of February, 1912.

JAMES F. McELROY.
